CHILD'S DIAPER SUIT OR SIMILAR ARTICLE

Ruth B. Allen, Elizabeth, N. J.

Application October 20, 1951, Serial No. 17,029

Term of patent 14 years

(Cl. D3—17)

To all whom it may concern:

Be it known that I, Ruth B. Allen, a citizen of the United States, residing in the city of Elizabeth, in the county of Union and State of New Jersey, have invented a new, original, and ornamental Design for a Child's Diaper Suit or Similar Article, of which the following is a specification, reference being had to the accompanying drawing, forming a part hereof.

I claim:

The ornamental design for a child's diaper suit or similar article, as shown and described.

RUTH B. ALLEN.
